UNITED STATES PATENT OFFICE.

ALFRED E. MARZOLF, OF CHICAGO, ILLINOIS.

TURN-TABLE.

SPECIFICATION forming part of Letters Patent No. 679,179, dated July 23, 1901.

Application filed September 17, 1900. Serial No. 30,224. (No model.)

To all whom it may concern:

Be it known that I, ALFRED E. MARZOLF, a citizen of the United States, residing at Chicago, in the county of Cook and State of Illinois, have invented certain new and useful Improvements in Turn-Tables; and I do hereby declare that the following is a full, clear, and exact description thereof, reference being had to the accompanying drawings, and to the letters of reference marked thereon, which form a part of this specification.

This invention relates to improvements in turn-tables for railroads or the like, and more particularly to that class of turn-tables in which the mechanism of a locomotive-engine supported thereon may be utilized to turn the table to any desired position.

The invention consists in the matters hereinafter described, and more fully pointed out and defined in the appended claims.

In the drawings, Figure 1 is a side elevation of a device embodying my invention. Fig. 2 is a top plan view of the same. Fig. 3 is a central transverse section. Fig. 4 is a horizontal section of the mechanism for locking the rollers. Fig. 5 is a side elevation of the same. Fig. 6 is an enlarged section of the central pivot-bearing.

As shown in said drawings, A indicates a pedestal located centrally beneath the turn-table and adapted to afford a pivotal support therefor.

B B indicate the sills of the turn-table, extending longitudinally thereof and provided at the ends with the trucks b b, adapted to run on the circle-track C, extending circumferentially around the pit in a familiar manner. Said turn-table is supported centrally on the pedestal by means, as shown, of a ball-bearing comprising a vertical pivot A', axially secured on the pedestal, and an inverted cup A², which incloses said pivot on the top and sides and is supported at its lower end upon a plurality of bearing-balls which are interposed between the same and the top of the pedestal and for which a ball-race is provided in the pedestal and cup. From said cup braces a a extend to the sills B B on each side and serve to hold said sills in varying relation to said cup. The sills are also rigidly connected together in the usual or any desired manner and are provided at

the top with cross-ties b' b', upon which are secured track-rails extending toward the center from each end of the turn-table. At the central part of the turn-table said track-rails are omitted, and in lieu thereof a plurality of parallel rollers B' B' of relatively small diameter (indicated in Fig. 2) are provided, which are designed to take the place of the rails in the central part of the turn-table and to be engaged by and support the driving-wheels of the locomotive in turning the table. Said rollers B' B' may be of uniform diameter from end to end and provided at each end with a groove designed to receive the track-wheel flange. As shown, however, the same are provided on the ends, in alinement with the rails, with wheels or trucks b² of greater diameter than the central part of the roller, as indicated in Figs. 2 and 3, which support the driving-wheels when the engine is supported on the turn-table in position to be turned.

The pedestal A is provided at its top with a fixed gear a'. Supported in brackets D D' on the sills are vertical shafts D²D³, each provided at its lower end with a gear adapted to engage the gear a' and provided at its upper end with a bevel-gear d, adapted to engage the bevel-gear b³b³ on the central rollers B' B'. Said gears are so arranged, as shown in Fig. 2, that rotation of the rollers by the drivers of a locomotive acts to cause rotation of the vertical shafts, and thereby the swinging of the table.

E E indicate bars for locking the rollers from rotation while running a locomotive on or off the turn-table. Said bars are located one on each side of the turn-table and are provided with a plurality of longitudinal slots adapted to fit over the reduced extended axes of the rollers. On the inner side of said bars are provided a plurality of pins e adjacent to one end of each slot and adapted to engage notches in the trucks b² b² adjacent thereto, which are provided in the end of the same for that purpose. Said notches are so proportioned and said teeth are so adjusted that when said bars E E are moved in one direction to the limit of their movement said pins e are out of engagement with said rollers and said rollers are free to rotate. When, however, the bars are moved in the other direc-

tion to the limit of their movement, said pins *e* engage in said notches in said rollers and effectually lock the same from rotation. Levers *F* are provided one at each end of each 5 bar *E* and affording means whereby the engineer or fireman located in the cab of the locomotive may shift said bars either to their locking or unlocked positions. Obviously said rollers may be journaled in any desired 10 manner on the sills *B* *B*.

The operation of my device is as follows: Said turn-table being adjusted with the rollers locked by means of the bars *E* *E*, a locomotive may be moved thereon. Said rollers 15 being of small size, material jolt or jar to the locomotive running over the same is avoided. When in position on the table to be turned, the drive-wheels of the locomotive are supported on and engage the rollers. The bars 20 *E* *E* are now moved backwardly until the pins thereon are out of engagement with the rollers, leaving said rollers free to turn. If steam is now given the locomotive, the rotation of the drivers causes rotation of said rollers and one or more of the vertical shafts, the gear on the lower end of which acts against the fixed or non-rotative gear *a*, with the effect of causing the turning of the turn-table. Obviously the locomotive being at all times 25 under the control of the engineer he may adjust the turn-table with respect to the desired track with very little difficulty. The turn-table being free to move in either direction, the speed and extent of its rotation will be 30 entirely dependent upon the rotation of the drivers. Having once adjusted the table to the desired track, the levers *F* are shifted to throw the teeth *e* on the bars *E* *E* into engagement with the rollers, thereby locking 35 the same from rotation. The locomotive may 40 then be run off the turn-table in the usual manner. Obviously many features of construction may be modified without departing from the principle of my invention.

45 I claim as my invention—

1. In a turn-table the combination with the sills, of track-rails secured on each end of the same, a plurality of transverse rollers located centrally of the turn-table and adapted to engage the driving-wheels of a locomotive when balanced thereon, operative connection between said rollers and a part rigidly secured to the foundation whereby said turn-table may be operated by the drive-wheels of the 55 locomotive and means operated from the cab of the locomotive for locking said rollers from rotation.

2. In a turn-table a plurality of parallel transverse rollers located centrally and adapted to engage the driving-wheels of a locomotive when balanced on said turn-table, one end of each roller being provided with radial notches and a movable locking-bar provided with teeth or projections and adapted at one 65 limit of its movement to engage in said notches

of the rollers thereby locking the same from rotation.

3. In a device of the class described the combination with a fixed pedestal and sills pivoted thereon of transverse rollers journaled intermediate of the ends on said sills and adapted to support the driving-wheels of a locomotive when balanced on the pedestal, a movable bar parallel with each sill and in alinement with the ends of the rollers and 70 means whereby shifting of said bars in one direction serves to lock the rollers from rotation and shifting of said bars in the opposite direction permits free rotation of the rollers. 75

4. In a turn-table the combination with a fixed pedestal and parallel sills pivoted thereon, of a plurality of transverse rollers journaled intermediate of the ends of said sills the tops of the same being in alinement with the top surface of the track-rails at the ends 80 of the turn-table, means adapted to be operated from a locomotive-cab when balanced on said turn-table for locking said rollers from rotation and vertical shafts secured centrally of the turn-table between the sills and 85 provided at the upper end with beveled gears adapted to intermesh with like gears on said rollers, the lower ends of said shafts being provided with gears adapted to intermesh with a fixed gear on said pedestal. 90

5. In a device of the class described the combination with a plurality of transverse rollers journaled close together on the sills of a turn-table of a locking mechanism for said rollers comprising a bar slidably supported 95 on each sill in alinement with the ends of the rollers and complementary parts on said roller ends and said bars adapted to interlock when the bars are moved in one direction and to be out of engagement when the bars are moved 100 in the other direction.

6. In a device of the class described the combination with a plurality of transverse rollers journaled close together on the sills of a turn-table of a locking mechanism for 105 said rollers comprising a bar slidably supported on each sill in alinement with the ends of the rollers, said bars being slotted to receive the reduced ends of the axis of the rollers, a pin at one end of each slot and complementary notches in the end of each roller adapted to receive said pins in locking engagement when the bars are in one of their adjusted positions and means for moving 115 both bars into or out of locking engagement 120 adapted to be operated from a locomotive-cab by a lever.

In witness whereof I have hereunto subscribed my name in the presence of two subscribing witnesses.

ALFRED E. MARZOLF.
